UNITED STATES PATENT OFFICE.

FLORENCE LYON PENTZ AND JAMES BOLTON PENTZ, OF NEW YORK, N. Y.

DIRECTION-INDICATOR FOR AIR AND MARINE CRAFT.

1,376,727.

Specification of Letters Patent.

Patented May 3, 1921.

Application filed February 23, 1918. Serial No. 218,646.

To all whom it may concern:

Be it known that we, FLORENCE LYON PENTZ and JAMES BOLTON PENTZ, both citizens of the United States, residing at New York, county of Richmond, and State of New York, have invented certain new and useful Improvements in Direction-Indicators for Air and Marine Craft, of which the following is a full, clear, and exact description.

This invention relates to combined compasses and levels for aircraft, particularly airplanes, and its chief object is to provide a simple and reliable device which will indicate to the aviator the direction of flight both in the horizontal and the vertical plane. Another object is to provide for the purpose a device which will give trustworthy readings not only when the craft is on an even keel but also when inclined at any angle laterally or fore-and-aft, and even when flying upside down.

To this and other ends the invention consists in the novel features and combinations hereinafter described.

Our invention contemplates the use of a device tending to point in a constant direction with respect to the points of the compass, and a device tending to point constantly toward the zenith. These elements which may be conveniently realized in practice by a magnetic compass needle and a support for the same which will act in the manner of a plumbline, so to speak, are immersed in a body of liquid contained in a suitable transparent receptacle, preferably a spherical globe. The receptacle is movable freely about the body of liquid, practically the only opposition to such movement being the slight friction or drag between the two; and by preference the aforesaid devices are so shaped as to impede their movement in or relatively to the liquid, thereby "locking" the said devices and the liquid together, as it were. The result is that the movements of the receptacle about the liquid have substantially no effect upon the aforesaid devices, which therefore continue to point in their normal directions.

Referring to the accompanying drawing, Figure 1 is a side view of one form of our improved compass.

Fig. 2 is a side view of the same, but with part of the globe broken away, and showing

the position of the device when the airplane or other aircraft is tipped or tilted at a steep angle to the horizontal.

Fig. 3 is a cross section of the preferred form of the invention.

Fig. 4 is a sectional plan view on line 4—4 of Fig. 3.

Our improved compass as illustrated comprises a hollow transparent globe 10, made of glass or other suitable material, and preferably having at least its inner surface as nearly spherical as possible. In the embodiments shown in Figs. 1 to 4 inclusive the globe is filled or nearly filled with a suitable liquid, preferably of low freezing point so as not to solidify when subjected to the intense cold often encountered in flight, especially at high altitudes. Among the liquids suitable for the purpose, alcohol and gasoline may be mentioned. To permit expansion and contraction of the liquid due to the extremes of temperature to which it is subjected a chamber 11 may be provided in the stem or neck 10^a of the globe, communicating with the interior by a narrow passage and closed on the outside by means of a yielding or elastic diaphragm, as 12, secured in position in any convenient manner. Or, by filling the globe not quite full, a bubble of air or other gas or vapor, preferably rarefied, 13, can be left inside. Or both these expedients may be resorted to. The portion containing the expansion chamber, and, if desired, the adjacent portion of the globe itself, may be made of metal, as in such parts transparency is not, in general, essential.

Immersed in the liquid in the globe is a magnetic needle 14, suspended by a rod 15 from a suitable float 16. The buoyancy of the latter or the weight of the parts supported by it is preferably such that the point or finger 17 at the top will at most barely graze the inner surface of the globe when the liquid is at about its maximum density. In the embodiment shown, the needle 14 is rigidly attached to the bar or rod 15.

In order to put the center of gravity well below the float 16 a weight 18 is provided, preferably of non-magnetic material. In the present instance the weight is mounted on the stem near the lower end thereof. To damp the needle and thereby diminish its movements relative to the liquid in which the parts are immersed, the stem is made of a

flat bar, or the needle, also made of similar shape, is set on edge. Or both these expedients may be resorted to, the plane of the stem being at right angles to the plane of the needle so as to diminish the tendency to swing as a pendulum relatively to the liquid, while the needle itself opposes rotary vibration within the liquid. On the other hand, vibration, as from a racing engine or motor, tends to keep the float from lagging and hence aids it in keeping its position at the extreme top of the globe as the latter is tilted.

The globe is preferably made in two parts, divided at the horizontal diameter. After the floating parts are inserted the globe-parts are secured together in any convenient and suitable manner, as by means of insoluble cement, so as to make a liquid-tight joint. If necessary or desirable the joint so made may be reinforced with band 19, preferably of spring brass, which has a spherical inner surface so as to fit the globe snugly. The band may be a simple ring 25 of slightly smaller diameter than the globe, so that it can be sprung into place.

In the preferred embodiment, Figs. 3 and 4, the stem 15 carries a compass card 20, reaching nearly to the wall of the globe, 30 and the stem is of such length as to position the card at the central horizontal plane of the globe, as shown. The card, which is preferably made of non-magnetic metal, as brass or aluminum, may be marked 35 with the points of the compass like the mariner's compass or in any other convenient and suitable manner. For indicating azimuth, or horizontal direction, marking of some sort on the card is of practical importance if the needle is below the card, as 40 in Figs. 3 and 4. Both sides of the card may be marked, so that when flying upside down the points of the compass can be read; and the two sides may be of different colors, 45 for example, white and red, so that they can be distinguished at a glance.

The only impediment to the rotary movement of the globe (in any plane), relatively to the body of liquid inside, is the skin-friction between the two. This being very slight considering the total mass and therefore the considerable inertia of the liquid, the globe exerts but little drag on the liquid. Hence when the globe is fixed to 55 the airplane (and is therefore stationary relatively thereto) the rotary movement of the globe in any plane as the airplane changes the direction of its flight is communicated to the liquid only to a slight extent, if at all. In short, the globe rotates around the liquid. The normally slight tendency of the liquid to turn with the globe is further reduced by the reluctance of the needle (and hence of the parts connected with it) to depart from the north and

south direction, which reluctance is communicated to the liquid by the resistance to movement of the parts relatively to the liquid by reason of the skin-friction of the liquid and such parts and by the flat shape 70 of the card, needle and stem. In other words, the needle and connected parts tend to remain always in the position established by the needle under the influence of the earth's magnetism, and the liquid clings to 75 the needle and other parts so that the liquid itself tends to remain in the position established by the needle. Hence the liquid and the parts immersed therein act more or less as a solid body about which the globe is 80 freely movable. The result is that as the airplane tilts and turns, the needle continues to point to the north, the stem maintains its vertical or plumb-line position, and the card and needle maintain the horizontal position. The globe is preferably 85 marked or graduated, as for example with horizontal and vertical circles, like parallels of latitude and meridians of longitude on a terrestrial globe. Then as the 90 globe turns about the liquid and the compass-parts therein, fore and aft, side-wise, or in any other direction, the circles or other graduations are carried past the relatively stationary parts immersed in the liquid. 95 Thus if the air-plane changes the directions of its flight in the horizontal plane the meridians turn clockwise or counterclockwise, as the case may be. The vertical circle or meridian which is parallel to or in the 100 central vertical plane extending lengthwise of the airplane can be distinctively marked, so that the angle between such meridian or zero-circle and the point of the needle can be easily noted. If the airplane tips or 105 tilts in any direction, the "parallels" move past the index 17, the bubble 13, and the edge of the card 20, thus indicating the position or direction of the airplane with respect to the horizontal. One of the "parallels" 110 around each "pole" can be marked in a distinctive manner to indicate a degree of inclination beyond which it is particularly dangerous to go.

The method of supporting the globe 10 is 115 immaterial, and accordingly we have shown merely a simple base 25 in which the neck or stem may be fixed by means of cement or otherwise.

It is to be understood that the invention 120 is not limited to the specific devices herein illustrated and described but can be embodied in other forms without departure from its spirit. Nor is the invention limited to use on aircraft, since it may be employed 125 to advantage on other vessels, particularly submarines.

We claim:—

1. In a direction-indicator or compass for air-craft, a hollow globe filled with a 130

suitable liquid, a floating carrier therein, and a magnetic needle supported solely by the floating carrier and entirely unconnected with the globe, whereby the globe has unlimited freedom of rotation in every direction relative to the needle and at all times leaves the needle entirely free to maintain its normal position.

2. In a direction-indicator or compass for 10 aircraft, a hollow globe filled with a suitable liquid, a floating carrier therein, a compass-card and a magnetic needle rigidly attached to the card, supported solely by the floating carrier and entirely unconnected 15 with the globe, whereby the globe has unlimited freedom of rotation in every direction relatively to the needle and card and

at all times leaves the needle and card free to maintain their normal position.

3. In a direction-indicator or compass for 20 aircraft, a hollow globe filled with a suitable liquid, a float therein, a vertical stem carried by the float, and a magnetic needle carried by the stem, the needle being supported solely by the stem and float and being entirely unconnected with the globe, whereby the globe has unlimited freedom of rotation in every direction relative to the needle and at all times leaves the latter free to maintain its normal position. 25

In testimony whereof we hereunto affix our signatures.

FLORENCE LYON PENTZ.
JAMES BOLTON PENTZ.
